UNITED STATES PATENT OFFICE.

WILLIAM B. McMECHEN, OF McMECHEN, WEST VIRGINIA.

DESIGN FOR TEXTILE FABRIC.

SPECIFICATION forming part of Design No. 37,403, dated April 11, 1905.

Application filed February 10, 1905. Serial No. 245,140. Term of patent 14 years.

To all whom it may concern:

Be it known that I, WILLIAM B. McMECHEN, a citizen of the United States of America, and a resident of McMechen, county of Marshall, and State of West Virginia, have invented a new, original, and ornamental Design for Textile Fabrics, for an illustration of which reference is had to the accompanying drawing, in which the figure is a plain view of the textile fabric, showing the design.

I claim—
The ornamental design for textile fabric, as shown.

WILLIAM B. McMECHEN.
